HOLLOW CERAMIC THREE DIMENSIONAL WALL TILE

William M. Groff, 1045 Halifax Road,
Jacksonville, Fla. 32216

Filed Aug. 17, 1972, Ser. No. 281,470

Term of patent 14 years

Int. Cl. D25—01
U.S. Cl. D18—2 B

FIG. 1

FIG. 3

FIG. 2

FIG. 4

FIG. 5

FIG. 1 is a top plan view of the hollow ceramic three dimensional wall tile showing my new design;

FIG. 2 is a side elevational view thereof;

FIG. 3 is a bottom view thereof;

FIG. 4 is a cross-sectional view taken along line 4—4 of FIG. 1; and

FIG. 5 is a top isometric view thereof.

I claim:

The ornamental design for a hollow ceramic three dimensional wall tile, as shown.
